UNITED STATES PATENT OFFICE

GEORGE A. WOODMAN, OF CHICAGO, ILLINOIS, ASSIGNOR OF ONE-HALF TO WILLIAM O. BELT, OF CHICAGO, ILLINOIS

COMBINATION FREIGHT CAR SIDE AND GRAIN DOOR

Application filed July 11, 1930. Serial No. 467,216.

This invention relates to a novel car door and more particularly to a door adapted for use on a freight car.

The salient object of the invention is to provide a novel door for a freight car or the like which may be used in all respects in a manner similar to the usual door and which will include removable portions that may be used to provide a closure for the door opening to adapt the car for grain shipments thereby providing what is known as a grain car door. An ancillary object is to arrange the removable portions providing the grain car door for expeditious removal and re-placement and to so store the portions that the normal use of the door will not be impaired. By so arranging the door structure it will be possible to provide portions which will always be ready for use and it will therefore not be necessary to employ boards or other loose articles to provide a grain car door and because the portions may be easily stored when not in use, they may be used over and over.

Other objects of the invention are to provide a sturdy door which may be economically manufactured from relatively inexpensive material in an inexpensive manner.

A selected embodiment of the invention is illustrated in the accompanying drawings, and therein,

Fig. 1 is an elevational view looking from the interior of the car showing my improved door structure;

Fig. 2 is a vertical sectional view taken substantially on the line 2—2 of Fig. 1 and drawn to an enlarged scale;

Fig. 3 is a horizontal sectional view taken substantially on the line 3—3 of Fig. 1 and drawn to an enlarged scale;

Fig. 4 is an elevational view showing the removable portions as arranged to provide a grain car door;

Fig. 5 is a sectional view taken substantially on the line 5—5 of Fig. 4; and

Fig. 6 is a sectional view taken substantially on the line 6—6 of Fig. 4 and drawn to an enlarged scale.

Referring to the drawings wherein a selected embodiment of my invention is illustrated,

7 generally indicates a reenforcing frame that includes an upper strip 8, a lower strip 9, and side strips 10 and 11. The frame 7 is disposed toward the interior of the car when the door is arranged in position, the door being mounted in the usual manner to slide to and from closing position with respect to the opening provided in the side of a freight car. The door plate 12 may be made of a single sheet or it may be built up of two or more sheets and is stamped to provide pockets in which grain car door members are held in storage position until required for use. On the plate 12 there is an upper marginal portion 13, a lower marginal portion 14, and side marginal portions 15 and 16. The marginal portions 13, 14, 15, and 16 are disposed upon the outwardly disposed faces of the strips 8, 9, 10, and 11 and the plate 12 and frame 7 are joined by rivets 17 or other suitable securing devices. The marginal portion 13 is dished in the center portion thereof to provide a corrugation 18, a similar corrugation 19 being provided in the marginal portion 14. The marginal portions 15 and 16 are dished substantially throughout the length thereof to provide corrugations 20 and 21. The corrugations serve to reinforce the plate 12, additional reinforcement being provided by the frame 7. Inwardly of the marginal portions sections 22 of the plate 12 are bent to provide substantially dish shaped pockets 23. A rib 22' is defined between the sections 22 and this rib is disposed at the medial portion of the plate 12. The edges 85 of the door are arranged similar to the edges of the common type of freight car door. Along the outer edges of the strip 10 and marginal portion 15 a channel bar 24 is secured with the flattened bight portion thereof 90 disposed to provide an abutting surface 25 that serves as a stop to locate the door in closing position over the opening. Along the edges of the strip 11 and portion marginal 16 a channel bar 26 is fixed which cooperates 95 with a channel bar on the car frame to provide what is known as a spark arrester. A door of the above construction is provided with rollers arranged to travel on the slide commonly provided on freight cars and

therefore this door may be used in the manner of the usual freight car door.

To arrange a freight car for grain shipment it is now the general practice to fasten boards over the lower part of the door openings in the sides of the car, and supplies of these boards are provided conveniently during the grain shipping season. These boards often fit poorly and require special means to prevent the grain from leaking out. Often suitable boards are not provided which causes delay in loading and this represents considerable waste. My invention overcomes all these disadvantages by providing grain door members designed for this purpose only, which are carried by the car doors when not in use, which will form a close seal for the lower part of the door opening, and which are intended for repetitious use. The grain door members 27, 28 are securely held in pockets 23 of the car door, when not in use, by suitable means shown comprises brackets 29 fastened on the sections 22 at the lower ends of the pockets. These brackets provide ledges 30 extended at right angles to the sections 22 and at the inner ends of the ledges 30 are flanges 31 which extend parallel with the sections 22 but spaced therefrom and in the spaces thus provided, so as to rest on the ledges 30, I arrange the lower flanges 32 of the door members 27 and 28. On the sections 22 adjacent the upper ends of the pockets 23, at substantially the middle of said pockets, I provide brackets and pivotally mounted thereon are gravity latches 34 which engage the upper flanges on the door members 27 and 28.

At various points along the side edges of the sections 22 in the pockets 23 are angle strips 35 arranged end to end in vertical rows, the cooperating rows of angle strips being spaced apart in an amount equal to the width of the grain car door members whereby said angle strips will engage the side flanges 36 and 37 on said door members to prevent side movement of the door members. Since the lower flanges of the grain car door members are supported on the ledges 30 of the brackets 29 and are held against displacement therefrom by the flanges 31 and since the latches 34 engage the upper flanges of the door members and as the spacing between these members is substantially equal to the height of the door members, the door members will be held against vertical movement in the pockets 23, the strips 35 neatly engaging the side flanges 36 and 37 to prevent sidewise movement of the door members in the pockets.

When the car is to be arranged for grain shipment the door members 27 and 28 will be removed from pockets 23 by moving the latches 34 from retaining position, after which the grain car door members may be easily lifted from the pockets this being done prior to the time the door is moved to open

position. One of the door members 27 or 28 will then be arranged over the door opening and rested on either the side flange 36 or 37 and the other door member will be arranged thereover, these door members being disposed to extend transversely across the door opening and when arranged in this position these door members will close the opening in the amount required when the car is used for grain shipment, it being understood that the door may be moved back into closing position after the above arrangement of the members 27 and 28 over the opening, because these grain car door members are disposed within the car. The door members 27 and 28 arranged for use in this manner are disclosed in Fig. 4. In order to reenforce the door members 27 and 28, longitudinally extending dished portions 38 are provided which are extended in parallel relation, preferably in juxtaposition, and in this manner the door members are corrugated which manifestly reinforces them.

Both the side door openings are closed by the grain car door members when the car is used for grain shipments. After the grain has been emptied from the car, the door members 27 and 28 are again stored in the pockets 23 and the car may then be used for whatever purpose desired. Since convenient storage space is provided for the grain car door members, loss is to a great extent eliminated and therefore the disadvantages of present grain car doors are obviated.

The various elements of my door structure are corrugated and thus proper reenforcement is provided and therefore relatively light sheet metal may be used in the construction of these elements. Since relatively light sheet metal may be used it is manifest that the various members may be formed by stamping operations which are relatively inexpensive and therefore, since inexpensive material may be used which may be formed in an inexpensive manner it is manifest that I have provided an inexpensive construction. The device will be sturdy and sufficiently substantial to withstand the rather strenuous use to which such doors are put. Further since I have provided a convenient arrangement for storing grain door members which may be used to close the opening to arrange the car for grain shipments it is manifest that I have obviated the previously existing disadvantages. In addition to the above, the members providing closures for the opening for use in grain shipments may be securely fixed in position to prevent displacement thereof when the door is to be used in the manner of the usual freight car door.

While I have illustrated and described a preferred form of construction for carrying my invention into effect it is to be understood that I do not wish to limit myself to the precise details set forth but desire to avail my-

self of the invention within the purview of the following claims:

I claim:

1. A door of the character stated including a plate, said plate having sections thereof bent to provide a pocket, a member mounted in said pocket and removable therefrom to close a portion of the opening adapted to be closed by said door, and means in said pocket including a supporting ledge, a releasable means, and side movement preventing means for removably retaining said grain door member in said pocket.

2. A door of the character stated including a reenforced plate, said plate having sections thereof bent to provide pockets disposed outwardly of the inner face of the door, reinforced members detached from said door and mounted in said pockets and removable therefrom to close a portion of the opening adapted to be closed by said door, and means in said pockets for removably retaining said reenforced members in said pockets.

3. A door of the character stated including a sheet metal plate having the marginal portions thereof corrugated to provide reinforcements, sections inwardly of said reinforcements bent to provide pockets outwardly of the inner face of the door, and a frame mounted on the inner face of said plate.

4. A door of the character stated including a plate having the marginal portions thereof corrugated to provide reinforcements, sections inwardly of said reinforcements bent to provide pockets, a frame mounted on one face of said plate, and members mounted in said pockets and removable therefrom to close a portion of the opening adapted to be closed by said door.

5. A door of the character stated adapted to close an opening, said door including a plate having the marginal portions thereof corrugated to provide reinforcements and having portions intermediate said reinforcements bent to provide pockets with a rib intermediate said pockets, a frame for reinforcing said plate arranged opposite the corrugations thereof, and members retained in said pockets and removable therefrom to close a portion of the opening adapted to be closed by said door.

6. A door of the character stated adapted to close an opening, said door including a plate having the marginal portions thereof corrugated to provide reinforcements and having portions intermediate said corrugations bent to provide pockets, a frame cooperating with said plate and arranged opposite the corrugations thereof, members retained in said pockets and removable therefrom to close a portion of the opening closed by said door, and means in said pockets for retaining said members in said pockets.

7. A door of the character stated adapted

to close an opening, said door including a plate having the marginal portions thereof corrugated to provide reinforcements and having portions intermediate said reinforcements bent to provide pockets and having a rib intermediate said pockets, a frame cooperating with said plate and arranged opposite the corrugations of said first frame, members adapted to close a portion of the opening closed by said door, said members normally being retained in said pockets, means in said pockets for retaining said members in said pockets, said means including supporting ledges adjacent the lower ends of said pockets, latch members adjacent the upper ends of said pockets, and retaining members along the side edges of said pockets, said supporting ledge, latches, and retaining members being spaced apart to neatly receive said members when arranged in said pockets.
